Primary Examiner—Alan P. Douglas*Assistant Examiner*—Lavone D. Tabor[57] **CLAIM**

The ornamental design for a toothbrush and toothpaste travel case, as shown and described.

DESCRIPTION

FIG. 1 is a top perspective view of a toothbrush and toothpaste travel case showing my new design;

FIG. 2 is a side view thereof with the top in closed position, the opposite side being identical thereto;

FIG. 3 is a side view of FIG. 1;

FIG. 4 is a side view of FIG. 1 with the top being partially rotated;

FIG. 5 is a side view of FIG. 1 with the top rotated 180°;

FIG. 6 is a front view of FIG. 1 the rear being a mirror image;

FIG. 7 is a front or rear view of FIG. 2;

FIG. 8 is a bottom view FIG. 1; and,

FIG. 9 is a second embodiment of the travel case with the only differences residing in the width of the case, the number of compartments inside, and the number of openings on the top and bottom of the case.
